Des. 214,099
Patented May 6, 1969

214,099

SLIDE PROJECTOR

Thomas M. Steinbach, Park Ridge, and Robert M. Simonelli, Des Plaines, Ill., assignors to GAF Corporation, a corporation of Delaware

Filed Feb. 20, 1968, Ser. No. 10,657

Term of patent 14 years

Int. Cl. D16—03

U.S. Cl. D61—1

7-1 - 5 -

7-1 - 4 -

FIG. 1 - 7 -FIG. 2 - 6 -

FIG. 1 is a perspective view of a slide projector embodying our new design;

FIG. 2 is a front elevational view thereof;

FIG. 3 is a rear elevation thereof;

FIG. 4 is a left side elevational view thereof;

FIG. 5 is a top plan view thereof;

FIG. 6 is a right side elevational view thereof; and

FIG. 7 is a bottom plan view thereof.

We claim:

The ornamental design for a slide projector, substantially as shown.
